AEROPLANE

Nicholaus Franzen, Chicago, Ill.

Application February 14, 1935, Serial No. 6,571

3 Claims. (Cl. 244—25)

This invention relates to certain improvements in aeroplanes and more particularly to aeroplanes embodying the helicopter principle of vertical lift.

5 Further the invention has reference to an aeroplane provided with a dirigible motor which may be rotated from the vertical to the horizontal so that the same may be used either as a helicopter engine or for flying in a horizontal direction.

10 An object of the invention is to provide improved supporting means for the motor together with novel and efficient means for locking the motor in either vertical or horizontal position, as well as means for swinging the motor from the vertical to the horizontal or vice versa as desired.

15 The invention together with its objects and advantages will be best understood from a study of the following description taken in connection with the accompanying drawings wherein:

20 Figure 1 is a side elevational view with the motor shown in vertical position.

Figure 2 is a top plan view.

25 Figure 3 is a top plan view of one of the motor mount brackets.

Figure 4 is an elevational view taken at right angles to Figure 1.

Figure 5 is a detail view partly in section and partly in elevation.

30 Figure 6 is a vertical sectional view.

Figure 7 is a detail view taken substantially on the line 7—7 of Figure 2.

Figure 8 is a detail view showing a handle guide member.

35 Figure 9 is a detail view taken substantially on the line 9—9 of Figure 1.

Figure 10 is a fragmentary detail view partly in section and partly in elevation showing a latch structure hereinafter more fully referred to.

40 Referring in detail to the drawings, the numeral 10 indicates a fragmentary portion of the fuselage of an aircraft.

In accordance with the present invention there is suitably located and mounted on the top of the fuselage a dirigible motor 11 with which is associated a screw propeller 12.

45 The improved mount for the motor 11 consists of a pair of opposed substantially duplicate posts 13—13 which at their upper ends are provided with integral bearings 14 and gear housings 15, suitable caps 16 being provided for said gear housings. Journalled in the bearings 14 are hollow stub shafts 17 to the inner ends of which are secured for rotation therewith opposed por-

tions of a stream line casing 18 provided for the dirigible motor 11.

Also secured on the ends of the stub shafts 17 within the gear housings or casings 16 are gears 19 that are in constant mesh with worms 20 provided on the upper ends of shafts 21. The shafts 21 extend through tubular housings 22 formed integrally with the standards 13. Obviously, through the intermeshing gears 19 and 20 rotation of the shafts 21 is imparted to the motor 10 casing 18 causing the motor to swing vertically from a vertical to a horizontal position or vice versa as desired.

Arranged rearwardly of the standards 13 and disposed laterally inwardly relative to the standards 13 is a third standard 23 that has extending downwardly from the upper end thereof a longitudinally curved guide rail 24 braced intermediate its ends as at 25 and terminating at its lower end in an enlarged foot 26. On its concaved face 20 the rail 24 is provided with an integral rib 27. At its rear end the motor casing 18 is provided with a projection 18 having a channel or groove 28 that receives the rib 27 in a manner clearly shown in Figure 5 whereby provision is made for guiding the dirigible motor during its swinging movement and at the same time prevent undue lateral play or thrust of the motor.

For locking the motor in vertical position there is provided a latch mechanism which includes a 30 housing 29 cast integrally with the foot 26 of the guide member 24, and operating in the housing 29 is a spring pressed plunger 30 urged outwardly of the housing 29 into position rearwardly of the projection 18 through the medium of a coil 35 spring 31 disposed about the stem 32 of the plunger 31. Connected with the free end of the stem 32 is one end of a cable 33 trained over a suitable pulley 34 provided within the aforementioned housing 29.

40 For releasably securing the motor in the horizontal position there is provided at the upper end of the standard 23 a housing 35 which at one end merges into an enlarged socket 36 that is adapted to receive partially the projection 18 on the 45 motor casing 18. Projectible into the socket 36 from the housing 35 is a locking bolt or plunger 37 urged outwardly through the medium of a spring 38 disposed about the stem 39 of the plunger 37. Connected to one end of the stem 39 of the plunger is a control cable 40 that extends downwardly through the hollow standard 23. Internally of the fuselage the cables 33 and 40 are trained over suitably arranged pulleys 41, 42, and 43 and are suitably secured to one end of an 55

operating handle 44 the stem of which operates in a substantially tubular guide 45 secured to and depending from the ceiling of the fuselage as best shown in Figures 4 and 8. Obviously by pulling downwardly on the handle 44 the latch members 30 and 37 are retracted thus releasing the motor so that the latter may be swung in a vertical plane to either the horizontal or vertical position as desired.

- 5 10 15 20 25 30 35 40 45 50 55 60 65 70 75 80 85 90 95 100
- 10 For rotating the motor there is provided internally of the fuselage and on one end of one of the shafts 21 a hand wheel 46, and power is transmitted from said one shaft 21 to the other shaft 21 through the medium of a shaft 47 journaled in suitable bearings 48 suspended from the ceiling of the fuselage 10 and connected with the shafts 21 through the medium of bevel gearing 49. Obviously, by turning the hand wheel 46 shafts 21 will be caused to simultaneously rotate to thereby swing the motor to the desired position.

For feeding oil and fuel, such as gasoline or the like to the motor there are provided pipes 50 and 51 respectively, these pipes having end portions extending into the gear casing 15 and through the stub shafts 17 into the casing 18.

If desired, and as shown, the rear standard 23 is suitably braced by rods 52.

It will also be understood that arranged internally of the casing 18 may be an auxiliary tank for fuel, oil or the like, suitable means (not shown) being provided for access to such reserve tank.

Also and in actual practice, it is contemplated to house the standards 13 and 23, together with their associated parts in casing of stream line contour.

Having thus described the invention, what is claimed as new is:

1. In an aeroplane having a motor and a pro-

peller driven thereby, means for mounting said motor for swinging movement, a fixed arcuate guide provided with a rib, said guide at its respective opposite ends being provided with integral housings and stop members arranged in operative positions to said housings, said motor having a casing provided with a bifurcated projection engaging the rib of said arcuate guide, and spring projected latch members having a working fit in said housings and respectively co-operable with respective stops and the said projection of the motor casing for holding said motor against a casual swinging movement.

2. In an aeroplane having a motor and a propeller driven thereby, a pair of opposed standards between which said motor is mounted for vertical swinging movement, a fixed arcuate guide provided at its respective opposite ends with an integral housing, a spring projected latch member having a sliding fit in each housing, and said motor having an integral projection engaging said guide, and co-operable with said latch members, for securing the motor in either a horizontal or a vertical position, optionally.

3. In an aeroplane having a motor and a propeller driven thereby, a pair of opposed standards between which said motor is mounted for vertical swinging movement, gearing arranged within said standards and connected with the motor for positively swinging the latter, a fixed arcuate guide member provided at its respective opposite ends with integral housings, latch members having a sliding fit within the respective housings, said motor having an integral member engageable with said guide and co-operable with said latch members for securing the motor at either of two positions and mechanisms connected with said latch members for simultaneously retracting said latch members to release the motor.

NICHOLAUS FRANZEN. 40
